UNITED STATES PATENT OFFICE.

JULIUS DRUCKLIEB, OF JERSEY CITY HEIGHTS, NEW JERSEY.

IMPROVEMENT IN SKATES.

Specification forming part of Letters Patent No. 178,051, dated May 30, 1876; application filed February 5, 1876.

To all whom it may concern:

Be it known that I, JULIUS DRUCKLIEB, of Jersey City Heights, in the county of Hudson and State of New Jersey, have invented a new and Improved Skate, of which the following is a specification:

In the accompanying drawing, Figure 1 represents a side elevation; Fig. 2, a bottom view of my improved skate; and Fig. 3, a vertical transverse section of the same on the line *c c*, Fig. 2.

Similar letters of reference indicate corresponding parts.

My invention relates to such improvements in skates that the same may be instantly and rigidly applied to the heel and sole of the shoe.

The invention consists of improved heel and sole fastening devices.

In the drawing, A represents a skate, the heel-plate of which is provided at the under side with guide-lugs *a*, in which a slotted plate, B, slides, parallel to the runner in the direction of the longitudinal axis of the skate. A set-screw, C, turns in a screw-nut, *b*, cast at the rear part of the slotted plate B, and carries the same backward when turned, so that its end bears against the runner. The plate B may be moved forward when the screw is turned back. The plate B is cast at the front end with a bearing, *d*, for the pivot-pin of a swinging lever, D, that binds, by its broad spurred or pointed edge D', against the front part of the boot-heel, so as to bite into the same, and secure it tightly to the rear lugs D'' of the heel-plate. The set-screw C allows the adjustment of the skate to any size

of heel, while the swinging lever D produces, by being carried up until retained by a stop-lug, *e*, on the runner, the tight attachment of the skate to the boot-heel, releasing the same when the lever is lowered and the gripping of its sharp edge D' is discontinued. The front part of the boot or shoe is connected to the skate by an adjustable toe-holder, E; or it may be connected by the sole-binding side clamps F, of which one is set by a clamp-screw, while the other is slidden sidewise by a swinging lever, F', having an eccentric at its fulcrum, which works in a recess of the sliding clamp-plate. The lever F' is retained in place by means of a downwardly-bent side lug, *f*', at the outer end, which engages with the heel-lever D when the latter is seated on the rest or stop-lug of the runner. The front part of the skate is thus, equally with the heel, reliably secured to the foot.

What I claim is—

1. The slotted plate B, sliding in guide-lugs *a*, having a nut, *b*, with screw, C, and provided with a bearing, *d*, in combination with swinging lever D, having the pointed edge D', heel-plate having rear lugs D'', and runner having the stop-lug *e*, as and for the purpose described.
2. The combination of side clamps F, swinging lever F', having eccentric stud *f* and a downwardly-bent lug, *f*', and the heel-lever D, all arranged substantially as and for the purpose specified.

JULIUS DRUCKLIEB.
